UNITED STATES PATENT OFFICE.

ERNEST J. SWEETLAND, OF MONTCLAIR, NEW JERSEY.

PRESSURE-FILTER.

1,083,305.

Specification of Letters Patent.

Patented Jan. 6, 1914.

Application filed April 12, 1913. Serial No. 760,587.

To all whom it may concern:

Be it known that I, ERNEST J. SWEETLAND, a citizen of the United States, residing in the town of Montclair, county of Essex, and State of New Jersey, have invented certain new and useful Improvements in Pressure-Filters, of which the following is a specification.

My invention relates to means for filtering fluids of various kinds, particularly while under pressure, and is largely concerned with mechanism for quickly and efficiently causing the separation of sections of the shell for purposes of cleaning and the like.

In carrying out my invention I provide a filter of such construction that even very large units may be operated without manual labor in discharging the residues and cleaning the filter plates, and one from which the residual filter cake may be discharged without the aid of water, since in many localities the use of water for sluicing the residues from filter presses is commercially impracticable.

I also provide a construction of great strength to withstand internal pressure, in which a plurality of bolts may be used to lock the filter body in closed position, said bolts being adapted to operate in unison under the control of a single mechanism.

In the accompanying drawings which form a part of this specification, Figure 1 is an end elevation of the filter in closed position, showing the hydraulic operating cylinders and means of supporting the filter from above; Fig. 2 is a side elevation of the filter, partly in section, the section being taken on the vertical center line of Fig. 1; Fig. 3 is a transverse sectional view of the filter in position open for cleaning, showing a portion of the filter cloth removed near the top of the filter leaf to expose the screen which forms the inner structure of the leaf; Fig. 4 is a similar view of the filter in closed position, and Fig. 5 is an enlarged view of one of the swing bolts on the eccentric shaft.

Referring to the drawings in detail, the numeral 1 designates a semi-cylindrical casting member supported from above by the channel 2 and braces 3 and 4, the supporting members being omitted from Figs. 2, 3 and 4 for the sake of clearness. A second semi-cylindrical casing member 5 is attached to the upper casing member by means of hinges 6. Cam shafts 6 are mounted in bearings 7 on both sides of the filter body. A plu-

rality of swing bolts 8 are eccentrically mounted on the cam shafts. Each swing bolt carries a washer 9 and an adjusting nut 10. A corresponding plurality of pins 11 are set in the cam shafts on the same center line and engage the pins 12 of the swing bolts. The function and operation of these parts will be described in detail below.

A plurality of filter plates or leaves 14 are suspended within the filter body. Each of these comprises a circular screen 15 having a casting riveted thereto, into which is firmly screwed the nipple 17 which has a side outlet 18. The cap 19 holds the filter plate in place by engaging the threaded end of the nipple 17. By means of this cap the casting 16 is firmly seated against the recessed surface on the inside of the upper casing member. The filter plate is covered with filter cloth 14^a which forms the filtering medium. The opening 18 aligns with the pipe 20 which has the valve 21 and connects with the filtrate pipe 22.

The cam shafts 6 are provided with the cranks 23 which are pinioned to the connecting rods 24, in turn pinioned to the cross-head 25 slidably mounted on the guides 26. The cross-head is keyed to the piston rod 27 of the hydraulic cylinder 28 into which is fitted the piston 29. The cylinder 28 is provided with an inlet pipe 30 at the top and inlet pipe 31 at the bottom. A second hydraulic cylinder 32 has its piston rod 33 pivoted to the lower casing member 5 by means of the projecting arm 34. The piston 35 may be forced up or down to swing the casing member 5 open or closed by admitting a fluid under pressure through inlet 36 or 37 as the case may be. The gasket 38 which is inserted in a groove in the lower member 5 seals the joint when the sections of filter body are closed.

A pipe 41 entering through stuffing box 42, passes along the top of the filter from end to end. This pipe is provided with nozzles 43 which project into the spaces between the leaves. The handle 44 furnishes a means of rocking the pipe and diverting the streams from the nozzles, and beyond this may be placed valves, not shown, for controlling the admission of the fluid to be filtered, and of wash water.

In operating the filter, the filter body is first filled by introducing the sludge to be filtered through pipe 41, the fluid entering through nozzles 43. The pressure of the

fluid forces the clear liquid content through the filter cloth 14^a, and it passes through the spaces formed between the wires of the screen and then upwardly through the casting 16, nipple 17, and aperture 18 into pipe 20, through valve 21 into pipe 22. The solid matter contained in the fluid deposits upon the filter cloth 14^a in an even layer until the adjacent cakes of solid matter approach each other to within about one-half inch. The supply of fluid to be filtered is then discontinued and wash water simultaneously supplied through the pipe 41. There is no interruption to filtration during the change from sludge to wash water. When the cakes are sufficiently washed, the supply of wash water is cut off and the small quantity of surplus wash water which occupies the space between the cakes is drawn off through pipe 39 and valve 40, or air may be forced through pipe 41, expelling surplus water through the porous cakes. The next step is to discharge the cakes from the filter leaves. Water under pressure is admitted to the cylinder 32 through pipe 37, which puts the piston rod 33 in tension in readiness to hold the weight of the lower member 5. Water under pressure is now admitted to cylinder 28, through pipe 30, forcing the cross-head 25 downward into the position indicated by the dotted lines in Fig. 1, thus rotating the shafts 6 through connecting rods 24. As the shafts revolve, the eccentric mounting of the bolts 8 causes them to drop away from the lugs 13. When the shafts revolve to a point where the pins 11 engage the lugs 12, the bolts are caused to swing outwardly and assume the final position shown, leaving the lower member 5 supported only by its hinges 6^b and the rod 33. The pressure below the piston in the cylinder 32 is now gradually released, permitting the member 5 to swing entirely open, as shown in Fig. 3. The cakes adhering to the filter cloths are now disengaged by introducing air, steam, or water pressure into the interior of the leaves through pipe 22 and pipe 20, the cakes falling from the filter into any convenient receptacle below. The filter may then be closed by introducing pressure into cylinder 32 through the pipe 37, and then into cylinder 28 through pipe 31, thus raising the cross-head 25 and rotating the shafts 6 so as to bring the bolts 8 back to a vertical position to engage lugs 13. The bolts are then caused to tighten into place with the powerful leverage which the eccentric construction affords, and the two members of the filter are locked together to form a water-tight chamber ready to be filled again.

While I have illustrated and described only one specific embodiment of my invention, I realize that it is susceptible of broad application, and I do not desire to be lim-

ited to the precise construction shown and described. The filter chamber, for example, may be made of other than cylindrical form, and other means than hydraulic pressure may be used to actuate the device without departing from the spirit of my invention.

Having thus described my invention, I claim:

1. A filter press having a two-part casing, one of said parts being movable with relation to the other, a plurality of means for locking and releasing said parts, means for simultaneously controlling the movement of said locking means, and means for controlling the movement of one of the parts 80 of said casing.

2. A filter press having a two-part casing, one of said parts being movable with relation to the other, a plurality of means for locking said parts together mounted on the 85 stationary part and adapted to engage the movable part, and means for simultaneously controlling the movement of said locking means.

3. A filter press having a two-part casing, 90 one of said parts being movable with relation to the other, a plurality of means for locking said parts together mounted on the stationary part adjacent to the junction of said parts, and means for simultaneously 95 controlling the movement of said locking means.

4. A filter press having a two-part casing, one of said parts being movable with relation to the other, means for locking said 100 parts together comprising a plurality of tension members mounted on one of said parts and having portions adapted to engage the other part, and means for simultaneously controlling the movement of said 105 locking members.

5. A filter press having a two-part casing, one of said parts being movable with relation to the other, means for locking said parts together comprising a plurality of tension members mounted on the fixed part and having portions adapted to engage the movable part, and means for simultaneously controlling the movement of said tension members including a cam shaft and means on 115 said locking members engaging said shaft.

6. A filter press having a two-part casing, one of said parts being movable with relation to the other, and means for locking said parts together including a locking member affixed to one of the parts and having a portion adapted to engage the other part, and means for controlling the movement of said locking member acting when said parts are in locked position to move said locking 120 member longitudinally to release the stress therein, and then to withdraw it from engagement with said second-named part.

7. A filter press having a two-part casing, one of said parts being movable with rela- 130

tion to the other, means for locking said parts together including a tension member mounted on one of the parts and having a portion adapted to engage the other part, 5 and means for controlling the movement of said member acting when said parts are in locked position to move said member longitudinally to release the tension therein and then to swing it out of engagement with 10 said second-named part.

8. A filter press having a two-part casing, one of said parts being movable with relation to the other, means for locking said parts together including a plurality of tension members mounted on one of said parts and having portions adapted to engage the other part, and means for simultaneously controlling the movement of said locking members acting when said parts are in 15 locked position to move said locking members longitudinally to release the tension therein and then to swing them out of engagement with said second-named part.

9. A filter press having a two-part casing 20 comprising a fixed section and a movable section, means for locking said sections together including a plurality of tension members mounted on one of said sections adjacent to the junction of said sections and having portions adapted to engage the other section, and means for simultaneously controlling the movement of said locking members acting when said sections are in locked 25 position to move said locking members longitudinally to release the tension therein, and then to withdraw them from engagement with said second-named section.

10. A filter press having a two-part casing comprising a fixed section and a movable 30 section hinged thereto, and means for lock-

ing said parts together including a cam shaft mounted in fixed bearings and a plurality of tension members having portions engaging said cam shaft and portions adapted to engage the movable section and lock the 45 same against the fixed section by rotation of said shaft.

11. A filter press having a two-part casing comprising a fixed section and a movable section hinged thereto, and means for locking 50 said parts together including a cam shaft, a plurality of locking members having portions adapted to engage the cam surfaces on said shaft, and portions adapted to engage said movable section and engaging 55 means on said shaft, and members for causing the oscillation of said members about the shaft at a fixed point in the rotation thereof independent of the cam surfaces.

12. A filter press having a two-part casing, and means for locking said parts together including a cam shaft and a plurality of tension members having portions engaging 60 said shaft and portions engaging the casing and adapted to lock the same in operative position by movement of said cam shaft.

13. A filter press having a two-part casing, and means for locking said parts in operative position including a cam shaft, a 65 locking member engaging said shaft, and means for causing a movement of said member at a fixed point in the rotation of the cam shaft independent of the cam surface of said shaft.
